UNITED STATES PATENT OFFICE

FERENC SZALAY, OF BUDAPEST, HUNGARY

DEVICE FOR THE PREVENTION OF THE TILTING MOVEMENT OF CURRENT COLLECTOR BOWS

Application filed October 18, 1923, Serial No. 313,344, and in Hungary October 31, 1927.

This invention relates to a device for the prevention of tilting of the bow of a movable current collector where such tilting would damage the contact wire while allowing the 5 same to move in a proper direction. Such a device consists for instance of an abutment fixed on the trolley frame below the bow, but this abutment may be used only in trolley frame devices deflecting only in one direction 10 and which abutment is to be turned together with the trolley frame about a vertically arranged axis, when the direction of the vehicle is to be changed. In trolley frames inclining in both directions only such arrangements 15 are known for the prevention of the tilting in which the bow is fixed by means of a wire-rope or of rods having a spring to allow the tilting, in which case the bow moving to the proper position with relation to the overhead 20 wire has to move also these means and overcome the elasticity of the same. Besides, these means are disadvantageous in use, because joined with the bow they must be exchanged, when the bow is exchanged and be- 25 cause it is necessary to correct continually these means, when the bow or the trolley frame is deformed.

The present invention removes the above explained faults by providing an abutment 30 about the horizontally arranged axis of the bow, which abutment guides said bow, whereby the bow may turn to the proper position. The abutment guided in the manner of a parallelogram remains horizontal independ- 35 ently of the position of the trolley frame and may be used therefore in trolley frames tilting in both directions.

According to the other form of the present invention the abutment is guided by the 40 means of a pair of bevelled gears and a rod under influence of torsion, in this way preventing great disarrangement of the abutment, besides it is possible in this arrangement to remove the torsion rod together with 45 the trolley frame from the support frame, so that the exchange of the current collector frame may be quickly effected in case of a damage or deformation.

The figures of the drawing show the in- 50 vention, Fig. 1 showing the side view of the

first arrangement and Fig. 2 the front view of the same arranged on a trolley frame tilting in both directions. In the Fig. 3 the tilting trolley frame is arranged not directly on the roof of the vehicle but on a pantograph frame. The arrangement with the bevelled wheels is shown in a side and in a front view in the Figures 4 and 5 arranged on a trolley frame which can deflect in both directions and in the Figure 6 arranged on a pantograph 55 shown in the side views. 60

As the Figures 1 and 2 show the current collector bow "a" pivotally supported by means of brackets c_1 and c_2 on the axis t_1 which is a part of the trolley frame k the bow 65 being secured against tilting by means of the abutment u supported on the axis t_1 and having the form of a double-armed lever, the points A_1 and A_2 of this lever being connected by the means of wire ropes d_1 and d_2 to the 70 points A_3 and A_4 of the support frame. In order to insulate the wire-rope each rope is composed of two parts connected by means of an insulating-body e_1 , e_2 . Instead of the 75 wire-ropes rods may be used, but it is preferred to use only one rod, because the same may be put under pressure. The end parts of the rod may be arranged also below the end parts of the trolley frame k in case the abutment u is provided with an arm directed inwards and the rod is connected to this arm. 80

In the Fig. 3 the trolley frame k is arranged on a pantograph p , in which the points A_3 and A_4 are provided on the lever u_2 the lower arm of which is secured by means of springs r_3 and r_4 in a determined position. Also a rod could be used instead of the 85 springs; in this construction also a bushing is necessary sliding about the lower arm of the lever u_2 and these rods are then pivotally connected to the bushing and to the arms of the pantograph. 90

In the Fig. 1 the abutment u and in the Fig. 3 the abutment u_1 is parallelly arranged with the line connecting the points A_3 and A_4 . The springs r_3 and r_4 could be replaced also by weights. 95

It is remarked that in using a weight the axis of the lever need not lie in the axis t_2 , the same may be everywhere on the trol- 100

ley frame *k*. It is also remarked that the current collector bow need not be formed of one plate, the same could be composed also of more plates.

In the arrangement according to the Figures 4 and 5 the current collector bow *a* is pivotally supported on the axis *t*₁ of the deflecting bow *k* by means of brackets *c*₁ and *c*₂. Independently of the same, a toothed wheel *u*₃ together with a pin *b* is supported on the axis *t*₁, the toothed wheel having the form of an abutment. A toothed wheel *u*₄ is secured to tube *d*₃ by means of screw *s*. Tube *d*₃ is guided by the pin *b*. Tube *d*₃ is non-rotatably connected to a tube *d*₄ by a rod *z* which has a slot and wedge connection with tube *d*₃. This wedge transmits the torsion from *d*₄ by means of the rod *z* secured to *d*₄. The rod *z* is preferably of an insulating material in order to prevent the conduction of the current through the toothed wheels.

On the lower axis *t*₂ of the deflecting trolley frame *k* is arranged the pair of the bevel gears corresponding to the upper pair of bevel gears *u*₃ and *u*₄, but *u*₃ is reversely arranged as in the front view, on the other side of the rod *d*₄ and fixed to the support *m*₁ by the means of the bolt *v* in order to hold in this way the upper abutment *u*₃ always in a parallel position to the lower *u*₃.

Between the upper abutment *u*₃ and the bow *a* is provided free room, which enables the bow to follow the different undulations of the conduct wire.

The same arrangement is shown in the Figure 6 on a pantograph *p*, in which a pin *n* is provided on the lower abutment *u*₃. The pin is to be held in the vertical position by the means of a bushing *o* sliding on the same and retaining it in a vertical position by means of rods *l*₁, *l*₂ connected to the bushing and to the arms of the pantograph. The reference letters for the equivalent parts of the devices are the same in the Figures 4, 5 and 6.

The pin of *u*₃ in Figure 6 may be retained in a vertical direction also by the means of a weight; in which case the bushing *o* and the rods *l*₁ and *l*₂ are dispensed with.

Prolonging the slit *h* shown in the Figure 5 to the end of the rod *d* the rods *d*₃ and *d*₄ will allow disconnection, when the trolley frame of the current collector is removed, whereby the device may be quickly removed and in case the bow sticks the tube *d*₃ will be pushed down from the support frame of the current collector and the overhead wire will not be broken.

60 What I claim is:

1. A device for preventing the overturning of a collector bow rotatably arranged on the trolley frame, including an abutment arranged below the bow and spaced therefrom to permit a limited free swinging of the bow,

and means whereby the abutment is held in substantially horizontal position independent of the inclination of the trolley frame.

2. A device for the prevention of the tilting movement of a current collector bow as pivotally arranged on the trolley frame, comprising an abutment pivotally supported on the trolley frame below the current collector bow and spaced therefrom to permit said bow a limited free swinging movement, and means intermediate the trolley frame and the abutment to maintain the abutment in substantially horizontal position to prevent a tilting movement of the bow in excess of its permissible free swinging movement.

3. A device for the prevention of the tilting movement of a current collector bow as pivotally arranged on the trolley frame, comprising an abutment pivotally supported on the trolley frame below the current collector bow and spaced therefrom to permit said bow a limited free swinging movement, and means intermediate the trolley frame and the abutment to maintain the abutment in substantially horizontal position to prevent a tilting movement of the bow in excess of its permissible free swinging movement, said means comprising spaced elements connected to the terminal of the bow and to the trolley frame to provide a parallelogram.

In testimony whereof I affix my signature.
